UNITED STATES PATENT OFFICE.

EVAN EVANS AND JOHN DAVIES, OF LLANRWST, ENGLAND.

CLIP OR FASTENING.

SPECIFICATION forming part of Letters Patent No. 498,509, dated May 30, 1893.

Application filed February 1, 1892. Serial No. 419,858. (No model.)

To all whom it may concern:

Be it known that we, EVAN EVANS, iron-monger, and JOHN DAVIES, draper, subjects of the Queen of Great Britain, residing at 5 Llanrwst, in the county of Denbigh, Principality of Wales, England, have invented certain new and useful Improvements in Clips or Fastenings, of which the following is a specification.

10 This invention has for its object an apparatus or appliance for attaching braces or other articles to buttons or studs.

In the accompanying drawings:—Figure 1 is a perspective view of the clip or fastening; 15 Fig. 2, a back elevation; Fig. 3, a vertical section; Fig. 4 a vertical section showing the method of fastening.

Referring first to Figs. 1 to 4 inclusive:— We stamp, preferably out of a single sheet of 20 metal, a clip, consisting of a combined semi-circular hook A, a spring or tongue piece B and a buckle bar C, round which latter the strap sewing or lashing of the braces D or other article passes. E is a button, and F the 25 garment to which it is attached. The circular hook A consists of a flat plate or semi-circular-disk a, fitting over the face of the button or stud, and having a series of projecting lips or a projecting rim a' hooked over in the 30 form of a circular hook, so that, when the button is slid in, between these projecting lips a' and the plate or disk a aforesaid, the button will be held from escaping except in the direction of the tongue piece B and buckle 35 bar C. The buckle bar C is preferably formed of the body of the metal bent over and a piece cut out immediately in front of the bend. The body of the metal is preferably made wider at this point to allow a sufficiently wide 40 slot for the strap sewing or lashing. The spring tongue piece B is an extension of this bent over portion, and the body of the metal is perforated for it at b. The body of the tongue piece is bent with a perpendicular 45 face. This has to be forcibly pressed against the body of the clip to allow the button to enter the hooked rim. The moment, therefore, the button has passed, the spring tongue piece B is

allowed to spring into its natural normal position. The perpendicular face of the tongue piece 50 prevents the button from escaping from the hooked rim a'. The body of the metal is pressed outward at G so that it forms a guard for the tongue piece, and, when the finger is pressed on the tongue piece, the thumb can 55 be on this guard G, or vice versa. This prevents any chance of an inexperienced person pressing with the finger on the back of the tongue piece and also with the thumb on the end of the tongue piece, and thus defeating 60 his object. Where the guard is used, this is impossible.

Instead of making the spring tongue piece B an extension of the bent over portion, it may be made of a separate piece of metal, 65 and riveted or otherwise fixed to the body of the clip.

Figs. 5, 6 and 7 depict the tongue B stamped out of the metal and bent with a perpendicular face opposite the semi-circular hook A. 70 This has to be forcibly pressed down to allow the button to enter or be withdrawn from the hook. The buckle bar C is dispensed with, and, in its place, the brace strap is secured by bending the edges of the clip c and pressing the serrated portion into the strap. The tongue piece B is stamped with protuberances 75 d on each side, which, when the tongue piece is bent, come upon the solid sides of the body and thus prevent the tongue piece from being 80 forcibly drawn out too far.

The following are some of the advantages of the invention:—

First. The semi-circular hook which clips on the button or stud does not reach or touch 85 the thread which attaches the button to the garment. The button is, therefore, not nearly so liable to come off.

Second. It is a much easier and quicker way to attach the clip on to the button or stud 90 than to attach the ordinary brace straps to the button.

We declare that what we claim is—

A clip or fastening comprising a body having its lower end semi-circular, bent over inwardly creating a button receiving pocket, a

slotway in the opposite end of the body, a button retaining spring secured to the upper end of the body extending downwardly and projecting beyond the plane of the body, and 5 partially inclosing the upper side of the pocket, said spring being bent thence to pass through an opening in the body and having a head upon its free end and engaging with the pocket of the body, as set forth.

1c In testimony whereof we have signed our

names to this specification in the presence of two subscribing witnesses.

EVAN EVANS.
JOHN DAVIES.
